UNITED STATES PATENT OFFICE.

IRVING I. FRANKEL, OF CINCINNATI, OHIO.

CONVERTIBLE TROUSERS.

Application filed December 30, 1925. Serial No. 78,443.

To all whom it may concern:

Be it known that I, IRVING I. FRANKEL, citizen of the United States, residing at Cincinnati, in the county of Hamilton and State of Ohio, have invented new and useful Improvements in Convertible Trousers, of which the following is a specification.

The present invention relates to convertible trousers and more particularly pertains to so called "long" or "slack" trousers which may be readily converted into bloomers or so called knickerbockers.

It is well known that convertible trousers of the above mentioned type have been previously proposed but they have usually taken the form of trousers having detachable lower leg sections or the lower portion of the trousers have been folded or otherwise concealed while the trousers are worn as bloomers. In these types of garments neither a true bloomer or knicker pants has been provided, because of the lack of fullness in the leg portions as well as across the hips, or where such bloomers has been provided the pants have not had their proper shape when worn as "long" or "slack" trousers.

The object of the present invention is the provision of "long" or "slack" trousers, which may be worn as such until the wearer desires to convert them into bloomers or knickers, the trousers being so constructed that while they are used as "long" or "slack" trousers they have the proper shape and measurements as such, and when converted into bloomer trousers they have in all respects the additional fullness required.

A further object of the invention is to provide a trouser as just mentioned having relatively wide turned in side seams, the seams having spaced stitching so that the pants produce one style and by ripping one line of stitching additional fullness is obtained and a different style may be provided.

With these and other objects in view the invention resides in sundry details of construction, combination and arrangement of parts as will hereinafter appear.

In this specification and the annexed drawings, the invention is disclosed in the form in which it is considered to be the best, but the invention is not limited to such form because it is capable of being embodied in other forms; and it is to be understood

that by and in the claims following the description herein, it is intended to cover the invention in whatever form it may embody within the scope thereof.

In the drawings which show the preferred embodiment of the invention as at present advised,

Figure 1 is a front elevation of a pair of trousers constructed in accordance with the invention, with the front portion of one leg of the trouser broken away to illustrate the detail construction;

Figure 2 shows the trousers, as shown in Figure 1, turned inside out and with their lower leg portions severed preparatory to converting the trousers into bloomers or knickers;

Figure 3 is a front elevation of the leg band which is to be attached to the lower ends of the leg portions for bloomer trousers;

Figure 4 is a top plan view of the leg band shown in Figure 3;

Figure 5 is a front elevation of the bloomer trousers shown in Figure 2, partially constructed with the leg band applied to the lower end of one leg;

Figure 6, is a fragmentary enlarged detail view of the outer seam of a leg portion of the trousers, showing its construction in order to provide the usual side vent bloomers; and

Figure 7 is a fragmentary sectional view similar to Figure 6, showing the vent portion of the seam of the bloomer trousers in its complete form.

Referring particularly to the drawings in which like characters denote similar and like parts throughout the several views.

The trousers illustrated in Figure 1 are constructed generally in the usual manner having a waist portion A and leg portion B and C. The leg portions being provided with the inner and outer side seams 10 and 11 as usual. The pants may or may not be lined, but since it is customary to line trouser bloomers or knickers, the drawings illustrate a lining 12 extending from the waist to a point 13 below the knee of the trousers.

The invention resides particularly, in cutting the front and rear leg sections, (as well as their corresponding lining sections, when lining is used), according to the full bloomer pattern as clearly illustrated in Figure 2,

so that a portion of the trousers above the knee, at least, will have sufficient material to provide full bloomers or knickerbockers.

In the assemblage of the garment, however, the side seam portions, of the garment sections are each provided with a double row of spaced stitching 14 and 15, the inner row or line of stitching 14 extending the full length of the leg sections 10 while the outer row or line of stitching 15 may, and preferably does, terminate approximately at the point 13 below the knee portion. The inner rows of stitching 14 are made on a line corresponding to the pattern 15 and design of "long" or "slack" trousers, while the outer rows of stitching 15 are made on a line corresponding to the pattern or design of full bloomer trousers. Thus it will be seen that the trousers produced in 20 accordance with this invention may be worn as "slacks" until it is desired to convert the same into bloomer trousers, at which time it is only necessary to cut or sever the lower leg portions on a line substantially corresponding with the line 13, Figure 1, and to rip the inner rows of stitching 14 at both the inner and outer side seams 10 and 11.

There is provided with each pair of 30 trousers of this invention, two leg bands which may be applied to the lower leg portions when converted into bloomers. These leg bands are shown in Figures 3 and 4, and comprise an elongated strip 16 of fac-

35 ing material, such as the cloth of the suiting and a lining 17. The lining is stitched to the facing around its marginal edges by a row of stitching 18 except for the upper edge of the band, as illustrated in Figures 3 and 4, in which is inserted the lower end portions 13^a of the bloomers, see Figure 2.

The lower edge portions 13^a of the bloomers are suitably gathered when the bands 16 are applied and for convenience suitable

40 means may be provided at the lower edges 13^a to indicate where the plaits or gathers are to be taken, such as by notches 13^b in the lower edge on the lining 12.

The usual vent along the lower portion 50 of the outer seam of bloomer trousers is provided for by "finishing off" for a distance the edges of the front and rear leg sections at their outer side seams at a point immediately above the line 13, as particularly 55 shown at 19 and 20, of Figures 6 and 7, respectively. When converting the "slacks" into bloomers, the lines of stitching 14 and 15 on the outer seams are ripped for a distance corresponding to the length 60 above these finished edge portions 19 and 20, as illustrated in Figure 6, the portion 20 being folded over to the rear of the portion 19 and held by suitable means such as a line of stitching 21, as clearly 65 shown in Figure 7.

What is claimed is:

1. A pair of trousers composed of sections of material joined together, the sections of the leg portions being cut on a pattern to allow considerable fullness therein, 70 said leg sections being joined together longitudinally by a line of stitching outlining said fullness, and a second line of stitching along said seams and spaced from said first line of stitching to provide a trouser of less 75 fullness, whereby upon removal of the second lines of stitching greater fullness may be obtained.

2. A pair of trousers as set forth in claim 1 further characterized by means indicating 80 where said leg sections may be severed transversely for providing bloomer trousers when said second line of stitching is removed.

3. As a new article of manufacture, a pair 85 of long trousers convertible into bloomer trousers, said trousers including leg sections, means securing said sections together including double rows of spaced stitching joining said sections together and extending from an upper portion of the trousers to a point 90 about the knee portions thereof, one row of said stitching being removable to allow greater fullness in the garment when converted into bloomer trousers, said leg sections being adapted to be severed transversely below the knee portion when converting the garment into bloomer trousers, and leg bands, one attachable to each severed 95 end of said leg portions.

4. As a new article of manufacture, a garment 100 as set forth in claim 3, further characterized by said seam of each leg portion having its edge finished off at a point adjacent the knee portion and above a point where said leg portions are severed to provide a vent about the knee portion of bloomer trousers, when said stitching opposite said finished edge portion of the seam is broken or removed.

5. As a new article of manufacture, a 110 pair of long trousers convertible into bloomer trousers, said trousers including leg portions having the sections thereof cut according to bloomer pattern, a double row 115 of spaced stitching joining the inner and outer seams of the leg sections together, one row of stitching following the bloomer outline and terminating at a point about the knee portion of the leg sections, the other rows of stitching following the pattern of long pants having less fullness than the bloomer pattern, said leg portions being adapted to be severed transversely below the knee portion when converting the garment into bloomer trousers and the row of stitching following the long trouser design being removed, and means attachable to the severed end of each leg portion for completing the bloomer trousers.

6. As a new article of manufacture, a 120

garment as set forth in claim 5, further characterized by means for indicating where said leg portions may be severed and said seam of each leg portion having its edge 5 finished off at a point adjacent the knee portion and above a point where said leg portions are severed to provide a vent about the

knee portion of bloomer trousers, when said stitching opposite said finished edge portion of the seam is broken or removed.

10

In testimony whereof I have hereunto set my hand.

IRVING I. FRANKEL.
